UNITED STATES PATENT OFFICE.

CLARENCE L. DAVIS, OF EAST SAGINAW, MICHIGAN.

DESIGN FOR A FAN.

SPECIFICATION forming part of Design No. 18,792, dated December 11, 1888.

Application filed April 28, 1888. Serial No. 272,213. Term of patent 7 years.

To all whom it may concern:

Be it known that I, CLARENCE L. DAVIS, a citizen of the United States, residing at East Saginaw, in the county of Saginaw and State of Michigan, have invented and produced a new and original Design for a Fan, of which the following is a specification, reference being had to the accompanying drawing, forming part thereof.

10 In the drawing the figure represents a front elevation of my design for a fan.

The leading feature of my design consists of a flat fan-blade, circular in outline, having an ornamentation thereon which imparts thereto the appearance of a base-ball, and also a handle having the form of a base-ball bat.

15 The letter A indicates the fan-blade, which is circular in shape and provided upon its 20 face with a loop-line, B, in imitation of the

stitches forming the seam of a base-ball cover. The face of said fan-blade may also be so shaded as to give it a spherical appearance.

C indicates the handle of the fan, which is shaped in imitation of a base-ball bat. ²⁵

Having thus fully described the appearance of my design, what I claim as new is—

The design for a fan, which consists of a flat circular fan-blade provided with an ornamental surface having a loop-line, B, resembling stitches, the entire blade resembling a base-ball, and a handle resembling a base-ball bat, substantially as described. ³⁰

Signed at Detroit this 14th day of April, 1888.

CLARENCE L. DAVIS.
